UNITED STATES PATENT OFFICE.

JEROME BENJAMIN, OF LOS ANGELES, CALIFORNIA.

WALL FURNACE.

Application filed April 27, 1926. Serial No. 104,878.

This invention relates to a wall furnace.

The general object of the present invention is to provide a wall furnace which is adapted for heating two adjoining rooms from one 5 furnace.

Another object of the present invention is to provide a wall furnace which may be installed by forming a single opening in a wall and when installed, is adapted to heat 10 the rooms on both sides of said wall.

In accordance with the present invention, I provide a furnace including a housing which is adapted to be installed in an opening in a wall, which housing is provided with 15 heat emitting openings at opposite sides and with central heat generating and radiating means within the housing adapted to emit heat from both of said openings. Moreover, in certain forms of the invention, there is 20 provided a single fresh air inlet to the furnace which thus constitutes a single means for supplying heated fresh air to a plurality of rooms, and there is also provided a single flue for the heating means. Said fresh air 25 inlet also provides the air for burner consumption in the furnace so that the air supply in the rooms is not depleted for this purpose.

This invention together with various additional objects and advantages thereof, will 30 best be understood from a description of a preferred form or example of a wall heater embodying the invention. For this purpose, reference is made to the accompanying drawings in which I have disclosed the preferred forms of wall heaters embodying the 35 invention.

In the drawings:

Figure 1 is a front elevation of a wall 40 heater installed in a wall,

Figure 2 is a side elevation mainly in section on the line 2—2 of Figure 1,

Figure 3 is a perspective view of a modified form of wall furnace or heater.

Figure 4 is an elevation mainly in vertical section of a furnace or heater of Figure 3,

Figure 5 is an elevation of one of the heat radiating bricks or tiles employed in the 50 heater or furnace of Figures 3 and 4, and,

Figure 6 is a section on the line 6—6 of Figure 5.

Referring to the drawings, 2 represents a building wall between two adjacent rooms.

55 Said wall is provided with a single opening

3 for installation of heating means for both rooms, separated by said wall, the opening 3 being in this case indicated as generally rectangular in form. 4 generally indicates a wall furnace or heater provided with self-included means for the generation of heat to be emitted into the rooms at both sides of said wall, the heater 4 comprising a housing 5 of metal or other suitable material, having opposed heat emitting openings 6 60 and 7 for the different rooms. Said openings 6 and 7 may be partially covered with a screen or grating, if desired.

The housing 5 of the furnace or heater 4 is preferably formed by encasement members 70 8 placed around the sides of the opening for encasing the same and by two complementary side members 9 and 10 which are bolted or otherwise secured to the encasement members 8. The side members 9 and 75 10 are preferably generally rectangular in shape and have their central portions bent outwardly from the surface of the wall 2, as indicated in Figure 2.

The particular form of the invention illustrated in Figures 1 and 2 is intended to be adapted to permit separate regulation of the heating of the different adjoining rooms and is, therefore, illustrated as including a 80 central partition member 11 extending from the lower side of the furnace or heater up to near the top, said partition member 11 being hollow and providing a fresh air passage 12. The partition 11 is provided with a curved baffle 13 at its top to restrict the 85 upward motion of the air and gases within the furnace, above which there is indicated a flue 14 built in the wall 2 housing the furnace. At each side of the partition 11

are heat generating units which may be of 90 any desired or preferred form of construction indicated, however, as gas burners 15 and 16. Said gas burners 15 and 16 are shown as each provided with heat radiating 95 elements 17 and 18 which may be of any usual or preferred form such, for instance, as tile or brick having a large surface for the radiation of heat, the tile or brick being indicated as of hollow form so that the 100 gases and flames from the burners 9 and 10 may ascend within the heat radiating elements. The heat radiating elements 17 and 18 and the burners 15 and 16 are indicated 105 as preferably supported upon a lower plate 19 of the furnace which may be of any suit-

able construction, but preferably shuts off the flow of gas from below the furnace, except as supplied through the burners 15 and 16 or up through the fresh air passage 12. 5 The burners 15 and 16 are indicated as connected through a common supply line 20.

Below the furnace, there is indicated an air passage 21 for introducing fresh air to the furnace and the lower side of the housing is indicated as provided at 22 with apertures for admitting said fresh air to the base of the furnace or heater, from which the fresh air passes through apertures 23 in the partition 11 below the plate 19. There is 10 thus provided a passage for air from without the building up through the passage 12 in which it is heated and from which it may be all or in part discharged into the adjacent rooms heated by the furnace or heater. 15 The fresh air passes from air passage 21 through apertures 22, apertures 30 in wall 31 of the furnace base, through apertures 23 and air passage 12, and out through the apertures 32 at the top of said passage. 20 Apertures 24 are also indicated in the sides 25 9 and 10 of the housing below the supporting plate 19 for supplying suitable air to the burners 15 and 16.

The above described furnace or heater, it 30 can be readily seen, is adapted to heat both rooms separated by the wall 2, and the furnace or heater requires only a single opening to be cut in the wall 2 for its installation.

Now, referring to the form of the invention shown in Figures 3 to 6, inclusive, I 35 have therein shown a form of wall furnace or heater which is of special value and simplicity when it is desired to supply a single wall furnace or heater for heating two adjoining rooms without requiring that the heater should be separately regulable for independently heating each room. Said furnace or heater is shown as comprising the heater housing 5^a having complementary heat 40 emitting openings 6^a and 7^a at its opposite sides for serving the different rooms, the housing 5^a being indicated as including the opening encasement members 8^a and the two side members 9^a and 10^a. Below the openings 6^a and 7^a, the housing includes a supporting plate or shelf 19^a which supports a heat radiating member 17^a of novel construction, adapted to radiate heat in both directions. Said heat radiating member 17^a is 45 positioned above a burner 15^a, indicated as including twin burner heads supplied with gas from a line 20^a.

Above the heat radiating members 17^a, there is provided a damper or baffle 13^a for 50 deflecting the gases and impeding their upward progress, and above said damper or baffle is a flue 14^a for the furnace. The sides 9^a and 10^a of the furnace are indicated as provided with air apertures 24^a below the supporting shelf 19^a, which aper-

tures 24^a serve to admit air to the burners 15^a. Additional air may, if desired, be passed to the furnace through a fresh air flue 21^a in the wall in which the burner is secured. Burners 15^a receive gas from the line 20^a.

The heat radiating members 17^a are indicated as of a novel construction of tile or brick, including a central wall 25 and two opposed downwardly diverging perforated side walls 26 and 27.

With the furnace as illustrated in Figures 3 to 6 inclusive, all of the heat supplied to the heat radiating members 17^a is radiated therefrom into the adjacent rooms, no other partition being between the rooms.

While the particular forms of wall heaters and furnaces herein described are well adapted to carry out the objects of the present invention, it is understood that various modifications and changes may be made without departing from the invention, and the invention includes all such modifications as come within the scope of the appended claims.

I claim:

1. A wall heater comprising a heater housing adapted to be installed in a wall opening above the floor of a room, the heater housing resting upon the lower wall of the opening, the heater housing being provided with opposed heat emitting openings for serving the rooms on opposite sides of the wall, heat radiating means providing heat radiating surfaces facing said openings, and heat generating means mounted within the housing.

2. A wall furnace comprising a furnace housing adapted to be installed in a wall opening above the floor of a room, the heater housing resting upon the lower wall of the opening, a heat generating means mounted within the housing, a heat radiating means providing opposed heat and radiating surfaces, openings in opposed sides of said heater housing, a baffle above said heat radiating means, and a flue above said baffle.

3. A wall furnace, comprising a housing adapted to be installed in a wall opening above the floor of a room, the heater housing resting upon the lower wall of the opening, the housing including encasing members for the opening and complementary side members, the side members being provided with openings for the emission of heat, heat radiating means within said housing providing heat radiating surfaces facing said openings, and burners disposed below said heat radiating means.

4. A wall furnace, comprising a housing adapted to be installed in a wall opening above the floor of a room, the heater housing resting upon the lower wall of the opening, said housing including encasement members for the opening and complementary side mem-

bers, each provided with heat emitting openings, heat radiating means substantially centrally disposed within the housing and providing heat radiating surfaces facing said openings, burners below said heat radiating means, a baffle above said heat radiating means, and a flue thereabove.

5. A wall furnace comprising a furnace housing adapted to be installed in a wall opening above the floor of a room, the heater housing resting upon the lower wall of the opening, the furnace housing providing opposed heat emitting openings adapted to emit heat into the rooms on both sides of the wall, a supporting shelf in said housing below said openings, heat radiating members supported on said shelf, and provided with heat radiating surfaces facing said openings, and heat generating members mounted without 20 in said housing below said shelf.

6. A wall furnace of the class described adapted to be placed in a wall opening above the floor of a room, the wall furnace comprising a furnace housing adapted to be supported by the walls of said opening, the furnace housing providing opposed heat emitting openings adapted to emit heat into rooms on both sides of the wall, heat generating means mounted within said housing, heat radiating members adapted to radiate from said openings the major portion of the generated heat, and a baffle above said radiating means adapted to deflect the conducted heat from the housing walls.

35 7. A wall furnace adapted to be installed in an opening in a wall above the floor of a room, the furnace comprising a housing adapted to be supported in said wall opening, heat generating means within said housing, the heat emitting openings in said housing adapted to emit heat into rooms on both sides of the wall, heat radiating members within the housing operative to radiate the heat from said openings, and means for circulating air through the heater to conduct the unradiated heat from the housing walls.

8. A wall furnace adapted to be installed in an opening in a wall between two rooms, the furnace comprising a housing adapted to be supported in said wall opening, a central partition in said housing closing the major portion of said opening, a burner having a twin head for generating heat at opposite sides of said partition, and openings in said housing adapted to emit heat into the rooms on both sides of said partition.

45 9. A wall furnace adapted to be installed in an opening in a wall between two rooms, the furnace comprising a housing adapted to be supported in said wall opening, a central partition in said housing closing the major portion of said opening, a burner having a twin head for generating heat at opposite sides of said partition, openings in said housing adapted to emit heat into the rooms

on both sides of said partition, and heat radiating members above said burners on both sides of said partition.

10. A wall furnace adapted to be installed in an opening in a wall above the floor of a room, the furnace comprising a housing adapted to be supported in said wall opening, a hollow partition in the center of said housing closing the major portion of said opening, said partition providing an air 70 passage, heat generating means at both sides of said partition, and heat emitting openings in said housing adapted to emit heat into the rooms on both sides of said partition.

11. A wall furnace adapted to be installed in an opening in a wall above the floor of a room, the furnace comprising a housing adapted to be supported in said wall opening, a hollow partition in the center of said housing closing the major portion of said 80 opening, said partition providing an air passage, heat generating means at both sides of said partition, heat emitting openings in said housing adapted to emit heat into the rooms on both sides of said partition, said heat generating means comprising a burner with a twin head with burner heads at both sides of said partition, and heat radiating means mounted within said burners.

12. A wall furnace adapted to be installed in an opening in a wall between two rooms, the furnace comprising a housing adapted to be supported in said wall opening, a central partition in said housing closing the major portion of said opening, a burner having a twin head for generating heat at opposite sides of said partition, openings in said housing adapted to emit heat into the rooms on both sides of said partition, and a baffle supported above said partition and 105 closely adjacent the upper end of the housing arranged to deflect the heat away from the upper wall of the housing and through said housing opening.

13. A wall furnace adapted to be installed in an opening in a wall between two rooms, the furnace comprising a housing adapted to be supported in said wall opening, a central partition in said housing closing the major portion of said opening, a burner 110 having a twin head for generating heat at opposite sides of said partition, openings in said housing adapted to emit heat into the rooms on both sides of said partition, heat radiating members above said burners on 115 both sides of said partition, and a baffle supported above said partition and closely adjacent the upper end of the housing, arranged to deflect the heat away from the upper wall of the housing and through said 120 housing opening.

14. A wall furnace adapted to be installed in an opening in a wall above the floor of a room, the furnace comprising a housing adapted to be supported in said wall open- 130

ing, a hollow partition in the center of said housing closing the major portion of said opening, said partition providing an air passage, heat generating means at both sides 5 of said partition, heat emitting openings in said housing adapted to emit heat into the rooms on both sides of said partition, and a baffle supported above said partition and closely adjacent the upper end of the housing 10, arranged to deflect the heat away from the upper wall of the housing and through said housing opening.

15. A wall furnace adapted to be installed in an opening in a wall above the floor of a room, the furnace comprising a housing adapted to be supported in said wall opening, a hollow partition in the center of said housing closing the major portion of said opening, said partition providing an air passage, heat generating means at both sides of 20 said partition, heat emitting openings in said housing adapted to emit heat into the rooms on both sides of said partition, said heat generating means comprising a burner with 25 a twin head with burner heads at both sides

of said partition, heat radiating means mounted within said burners, and a baffle supported above said partition and closely adjacent the upper end of the housing arranged to deflect the heat away from the upper wall of the housing and through said housing opening.

16. A wall heater comprising a housing, a partition disposed centrally in said housing, heating elements disposed at opposed sides of said partition, a baffle disposed above said partition, and openings in the housing 30 on both sides of said partition.

17. A wall heater comprising a housing, a partition disposed centrally in said housing, heating elements disposed at opposed sides of said partition, a baffle disposed above said partition, openings in the housing on both sides of said partition, and an air passage through said partition through which 40 a draft of air is introduced by the heat of the heating element.

Signed at Los Angeles, California, this 20 day of April 1926.

JEROME BENJAMIN.
